FRANK J. MURPHY, OF FLORAL PARK, NEW YORK, ASSIGNOR TO S. W. FARBER, INC.,
OF BROOKLYN, NEW YORK, A CORPORATION OF NEW YORK

SWIVELED LAMP-SHADE SUPPORT

Application filed May 17, 1929. Serial No. 363,933.

My invention relates to a new and improved lamp shade support.

One of the objects of my invention is to provide a lamp shade support of simple and efficient construction whereby the lamp shade can be tilted to any desired angle, and will be firmly held in its adjusted position.

Another object of my invention is to provide a swiveled lamp shade support in which a plurality of springs are employed for imparting sufficient friction between the various parts of the device, so as to frictionally hold the lamp shade in any suitable adjusted position.

Other objects of my invention will be set forth in the following description and drawings which illustrate a preferred embodiment thereof, it being understood that the above general statement of the objects of my invention is intended merely to generally explain the same, and not to limit it in any manner.

Fig. 1 is a side elevation.

Fig. 2 is a top view.

Fig. 3 is a sectional view on the line 3—3 of Fig. 4.

Fig. 4 is a top view, partially in horizontal section.

Fig. 5 is a rear elevation.

The lamp shade S is preferably made of any suitable vitreous material whose interior may be white and whose exterior may be green. The lamp shade is provided with a rear arcuate flange to which a protective metal shell 2 is applied. The column or pedestal P of the lamp (which may be a reading lamp of the well known type) is connected by means of a suitable member N' to the coupling member 17 of the support.

As shown in Fig. 4, the coupling member 17 is provided with an annular extension 16, whose width is substantially one-half the width of the said coupling member 17. Likewise, and as shown in Fig. 4, the holder for the shade is provided with a rearwardly extending arm 3, which is provided with a ring-like extension 3' whose width is substantially one-half the width of the said coupling member 17. A square shaft 14 passes through a square hole in the extension 16

so that said shaft 14 cannot turn in extension 16. Annular end members 12 and 18 are located at the ends of the shaft 14, and they are held in position by means of nuts 11 and 11'. The end members 12 and 18 cannot turn with respect to the square shaft 14. The opening in the extension 3' is made of sufficiently large diameter to enable it to turn freely with respect to the square shaft 14. End compression springs 15 and 20 urge the end members 12 and 18 into firm frictional contact with the extensions 3' and 16. The shell 2 of the shade is clamped against a corresponding flange 8 of the holder 5 by means of a strap 9 and nuts N.

When it is desired to tilt the shade S, as indicated in dotted lines in Fig. 1, this can be readily done because the extension 3' can turn freely with respect to the square shaft 14. However, the frictional hold produced by the compression springs maintains the shade S in the tilted position because of the frictional grip exerted between the end members 12 and 18, and the member 16. The compression of the springs 15 and 20 can be regulated by means of the nuts 11 and 11'. It is obvious that a very simple and reliable device is thus produced which automatically holds the shade in any tilted position.

Likewise, while I have shown my invention applied to the shade for a reading lamp, which has a pedestal or upright P, it would not be departing from my invention to apply the device to any other type of lamp having a rigid support of any kind which would correspond in function to the pedestal or upright of a reading lamp.

I have shown a preferred embodiment of my invention, but it is clear that numerous changes and omissions could be made without departing from its spirit.

I claim:

1. A shade support for a lamp having an upright or the like, comprising a coupling member connected to said upright, said coupling member having an annular extension, a shaft non-revolubly mounted in said extension, a shade holder having an annular extension revolubly mounted upon said shaft, a hollow end friction member slid-

ably and non-revolubly mounted upon an outer end of said shaft adjacent the extension of the shade holder, a compression spring located within said hollow end friction member, and an additional end member mounted upon said shaft and adapted to hold said spring in compressed condition, so that said spring urges said end friction member into frictional contact with the extension 5 of the shade holder, said friction member and the extension of the shade holder having non-interlocking friction faces which are perpendicular to said shaft.

2. A shade support comprising an annular member which is adapted to be connected to an upright or the like, a shaft having a non-circular cross section, said shaft being non-revolubly mounted in said annular member, a shade holder including a second 15 annular member which is turnably mounted upon said shaft, a rigid friction member which is non-revolubly and slidably mounted upon said shaft, said friction member being perpendicular to said shaft and being 20 adapted to frictionally resist the turning movement of the second annular member, said second annular member and said friction member having non-interlocking friction faces which are perpendicular to said 25 shaft, said friction member having a non-circular bore which fits upon said shaft.

3. A shade support for a lamp comprising an upright or the like, comprising a shaft which is non-revolubly connected to the said 35 upright, a shade holder which is revolvably mounted upon the said shaft, a friction member which is non-revolubly and slidably mounted upon the said shaft, said friction member and said shade holder having cooperating friction faces which are non-interlocking and which are perpendicular to the 40 said shaft, spring means adapted to urge said friction faces against each other, said shaft having a non-circular cross section and 45 said friction member having a bore which fits upon said shaft.

4. A shade support for a lamp having an upright or the like, comprising a coupling member adapted to be non-movably connected to said upright, said coupling member having an annular extension, the width of said annular extension being substantially one-half the width of said coupling member, a shaft which is non-revolubly mounted in 55 said extension, a shade holder having an annular extension which is non-revolubly mounted upon said shaft, the width of said shade holder and of said extension being substantially equal to the width of said coupling member, and friction members which are slidably and non-revolubly mounted upon the shaft at the outer ends of said extensions, said friction members and said extensions having non-interlocking friction faces which 60 are perpendicular to said shaft, and addi- 65

tional end members which are connected to the ends of said shaft and projecting beyond said ends, and compression springs located intermediate said additional end members and the lateral walls of said friction members, said compression springs being adapted to produce frictional contact between said friction members and said extensions. 70

In testimony whereof I affix my signature. 75
FRANK J. MURPHY.
